A. BELDEN

NONFREEZING WATERING TROUGH

Filed June 9, 1924

Inventor

Arthur Belden

By Spear, Middlem, Donaldson & Hall

Attorney

UNITED STATES PATENT OFFICE.

ARTHUR BELDEN, OF HARVARD, NEBRASKA.

NONFREEZING WATERING TROUGH.

Application filed June 9, 1924. Serial No. 718,886.

To all whom it may concern:

Be it known that I, ARTHUR BELDEN, a citizen of the United States, and a resident of Harvard, in the county of Clay and State 5 of Nebraska, have invented certain new and useful Improvements in Nonfreezing Watering Troughs, of which the following is a specification.

This invention relates to a stock watering trough which is an improvement on that shown in my Patent No. 1,446,493 and Patent No. 1,497,202, and has for its primary object to produce a device of such a construction that the water therein will not 10 freeze during severe weather and will automatically maintain a constant level in the drinking portion of the trough.

Another object is to provide means to prevent the water in the device from becoming contaminated with mud, refuse, sticks or the like, which usually takes place whenever an open trough is allowed to remain as such in a barn-yard for any length of 15 time.

Other objects and advantages will appear as the description proceeds.

To this end my invention consists in providing a main reservoir into which the water enters, being regulated by any suitable automatic means. This supply is preferably located in a manner to reduce freezing danger to a minimum, such as by entering from the lower side thereof, which utilizes the natural heat of the earth. Communicating with this reservoir is a drinking trough of suitable construction, which trough is provided with a circulation system which will keep the temperature of the water therein above the freezing temperature.

Additional means are provided to prevent the circulation system from clogging, which will be more specifically described hereinafter.

In the drawings I have illustrated one embodiment of the portion of my invention which has been chosen for illustration only, as required by law, but it is understood that I do not wish to be limited to the construction, combination or arrangement of parts shown, as obviously various changes and modifications will occur to those skilled in the art, and still fall within the scope of the claims:

In these drawings:—

Figure 1 is a sectional elevation showing

the relation of the parts to the frost preventing medium.

Fig. 2 is a plan of one form of my device.

Fig. 3 is an end elevation of the drinking portion.

Fig. 4 is an end elevation of the water bottle, or heat reservoir.

In the embodiment illustrated, I provide a reservoir having water supply pipes entering at the bottom preferably passing underground below the frost penetration line to the source of supply. Suitable means are provided to automatically regulate the flow of water to the reservoir, as by means of a float valve operating in the usual manner.

A drinking trough communicates with the reservoir, said communicating opening below the water level in order that floating refuse will not be conducted into the drinking portion. This drinking portion is also provided with a circulation system which may include a coil of pipes or the like, having its trough-attached ends at different levels. If a system of this character is used, it has been found satisfactory to extend such pipes around the reservoir, the whole to be packed to a suitable depth with fresh stable manure which will warm the water in the circulation system, which because of the known principles of the thermosiphon, will keep the water in the drinking portion above the freezing temperature. Obviously the water in the reservoir will also be warmed to a certain extent by the direct contact of the heating medium with the walls thereof. If a portion of this circulation system is enlarged to form a water bottle, or the like, it will be found to hold the heat in a more efficient manner. It has been found desirable to construct a baffle or strainer plate over the opening in the drinking portion leading to the circulation system in order to prevent refuse from clogging the heating system.

If found desirable, the drinking portion may be provided with a suitably arranged covering and the reservoir may be provided with upstanding means to retain the manure in the place desired.

Referring now more particularly to the drawings, I have shown a reservoir 1, having a water supply pipe 2, entering at the side near the bottom thereof, the entrance to the reservoir being covered by a suitable

valve 3, including a float valve 4, or the like, and a lever 5 pivoted on a fulcrum 6 and supplied with a float 7, in the usual manner to regulate the water supply according to the desired level of the water.

6 An opening 8, is provided in the reservoir intermediate the normal level of water and the bottom of the trough, for the purpose above stated, said opening communicating by means of pipe 8^a with a water bottle 10^a. This portion may be of any desired shape, which will undoubtedly vary according to circumstances.

10 The circulation system as illustrated, has been found to be satisfactory and includes a hollow member 10 extending backwardly from the drinking portion on each side of the reservoir and behind the latter, terminating in an enlarged water bottle, or heat 15 reservoir 10^a. The inlet end 11, of this system is located below the outlet 12, in order that the convection current of the heated fluid may rise and pass outwardly through the opening 12, into the trough, the cooler fluid passing through opening 11, into the system and the cycle of heating repeated. Obviously this circulation 20 system may be greatly varied and I have illustrated this form merely because of its 25 simplicity.

30 I have shown a baffle or screen 13 located between the walls of the drinking portion of the trough, preferably extending to the bottom of the trough and held in position by lugs 17 and 18 on the bottom and sides of the drinking tank respectively, said baffle being provided with a series of perforations 35 14. A sediment cup 15 secured to the lower part of the baffle 13 rests on or near the bottom of the drinking tank 9, so that by removing the baffle or screen 13, all float-sam may be removed with it and the jetsam by the sediment cup 15.

40 45 I have shown a cover 16, hingedly connected to the rear wall of the drinking por-

tion, but any suitable means of attachment may be substituted therefore, or if found desirable the cover may be eliminated. I have likewise illustrated a removable cover 17, on the reservoir portion, but likewise, other arrangement of these parts may be found desirable.

I claim:

1. A drinking device including a drinking bowl, a reservoir provided with automatic feed, a heat circulating system having a hollow member provided with tubular connections between the top and bottom of said hollow member and the drinking bowl, tubular connections between the heat 55 circulating system and the reservoir, the heating system being imbedded in stable manure.

2. A drinking device including a reservoir having automatic feed, a drinking bowl, a heat circulating system comprising a hollow member, tubular connections between the top and bottom of the drinking bowl and the hollow member and a tubular connection between the hollow member and the reservoir the hollow member and circulating system being imbedded in stable manure.

3. A drinking device including an automatic feed and valve chamber, a drinking 75 bowl, a heated water circulating system comprising a hollow member inclined to the horizontal, tubes connecting said hollow member with said drinking bowl, the inlet end of the tube of the circulating system supplying water to the drinking bowl being covered by a screen, a supply pipe 80 connecting the valve chamber with the circulating system, the valve chamber and substantially all of the circulating system being 85 embedded in manure.

In testimony whereof I affix my signature.

ARTHUR BELDEN.
